MOLD FOR CASTING STEREOGRAPHIC PRINTING PLATES

William F. Huck, Richmond Hill, N. Y., assignor,
by mesne assignments, to R. Hoe & Co., Inc.,
New York, N. Y., a corporation of New York

Original application June 2, 1932, Serial No.
614,910. Divided and this application April
13, 1934, Serial No. 720,351

8 Claims. (Cl. 22—5)

The present invention, which is a division of copending application No. 614,910, filed June 2, 1932, for Molds for casting stereotype printing plates, relates to improvements in molds for casting stereotype printing plates, and has for its object the provision of certain means that will obviate the tendency of stereotype plates that are cast in molds of conventional type to become deformed when removed from the mold.

Another object is to provide a novel method and means for equalizing the absorption of heat from stereotype plates during the casting operation.

Another object is to provide a stereotype plate casting mold of a design and construction particularly adapted to produce printing plates comparatively free from internal stresses resulting in deformation and a tendency of the finished plate to become warped and develop cracks after removal from the machine.

A further object is the provision of an improved casting box or chamber for a stereotype plate casting machine that will insure the production or casting of printing plates of uniform characteristics and homogeneous structure.

A still further object is to provide means for delaying the cooling of selected areas of a stereotype plate during the casting operation in order to assure the production of printing plates free from defects in structure or configuration.

Other objects and advantages will be found in the details hereinafter set forth.

As is well known to those skilled in the printing art, one of the chief difficulties encountered in the casting of printing plates has been the marked tendency towards deformation of a certain percentage of printing plates when taken from the casting chamber or box. This is due to the uneven solidification of the molten stereotype metal in the mold whereby internal stresses and strains are developed in the printing plate arising from the unequal cooling of the opposite sides of the said plate or the unequal absorption of heat from the printing plate while still in the mold, by the opposite sides of the casting chamber.

The matrix which lines one side of the casting chamber during the casting process is of a composition having poor heat conducting properties, consequently the molten metal engaged against said matrix will cool more slowly than the molten metal that is in contact with the opposite and bare wall of the casting chamber, where it cools rapidly. The difference in cooling produces or sets up stresses in the exterior of the

plate, which will in many cases cause the said plate when taken from the casting chamber to warp or to develop fissures and cracks, and in curved plates there is also a tendency for the curved edges to straighten. The matrix side of the plate by the cooling process above indicated is subjected to tensional stresses, which is opposed by compressional stresses in the opposite side of the plate. Upon removal of the curved plate from the mold, these force couples will cause it to "cave-in" along its straight edge and "open-up" in its curvature. In particular, the edges or margins of stereotype plates have been found to cool more rapidly than the body portion resulting in a tendency to deformation in the finished plate which in the case of a curved plate frequently produces a "saddle" formation and "opening up" of same.

In accordance with the present invention, and as forming an important feature thereof, a stereotype plate casting device is provided having a novel mold or casting chamber particularly adapted to prevent unequal cooling of the opposite sides of a printing plate.

The invention will be best understood when taken in connection with the accompanying drawings in which:

Figure 1 is a side elevational view, partly in section of a stereotype plate casting machine embodying the invention;

Figure 2 is a front elevational view as seen in the direction of the arrow 2 of Figure 1;

Figure 3 is an enlarged vertical sectional view of a portion of the mechanism shown in Figure 1, with parts broken away;

Figure 4 is a transverse sectional view taken on line 4—4 of Figure 3, looking in the direction of the arrows;

Figure 5 is a view of the core member as viewed in the direction of the arrow 5 of Figure 3;

Figure 6 is a longitudinal sectional view taken on line 6—6 of Figure 5, looking in the direction of the arrows; and

Figure 7 is a transverse sectional view taken on line 7—7 of Figure 5, looking in the direction of the arrows.

The invention is embodied in a plate casting device A, which comprises a base 8, to which are fastened side frames 9 and the vertically positioned core or fixed member 10 of the casting mold or box.

Upon the side frames 9, the body portion or movable mold member 11 of the casting mold is adjustably positioned so that same may be swung from the horizontal position, shown in dotted

lines to the vertical position where it is operative to receive molten metal.

The adjustment of the movable mold member 11 is permitted by trunnions or studs 12, 13 formed or secured on the sides thereof, the said trunnions being provided with rollers 14, 15 which travel over curved tracks or surfaces 16, 17 arranged on the side frames 9. The body portion 11 of the casting mold may be manipulated or moved by the handles 18, and since the trunnions 12, 13 and tracks 16, 17 are arranged and located to support the said body portion 11 of the mold in balanced condition at all angles or positions, it will be understood that same may 15 be handled with comparative ease and without undue strain or effect on the part of the operator. The cooling of the core member 10 is provided by a water jacket or chamber 19 which may have a valve controlled inlet pipe 20 and an 20 outlet pipe 20'.

In accordance with the present invention and for the purpose of preventing too rapid a cooling of the edges or margins of a stereotype plate, the member 10 is formed or provided with 25 a recess or pocket 21 in which heat insulating material 22 is secured. In addition to the insulating material 22, a sheet or web of insulation 23 that may be paper or other suitable material for the purpose of preventing too rapid a cooling of one side or face of the body portion of the stereotype plate, may be secured to or wound on spindles or bars 24, 25 having squared upper ends 24', 25', the said spindles being rotatably secured to the frame or support of the core 30 member 10 and mounted in sockets as at 26 fastened thereto. Suitable means for locking the spindles 24, 25 to hold the sheet material 23 securely in the casting chamber are provided, which may be pawl-engaged gears 27, 28 on the 40 respective spindles 24, 25.

When the rods on which the paper insulation is engaged or wound, is turned, the said paper insulation, which is preferably of heavy stock, will be drawn tightly against the core wall formed by the fixed member 10, the coating opposite or matrix wall being formed by the movable or swingable mold member 11, which is lined by the matrix C. In order to clamp the sheet of paper 23 the use of which latter is optional, a pair of clamping members are employed, each consisting of a band or strap 29, the ends 31, 32 of which are secured by screws 33 to bars or shafts 34, in which adjusting screws 35, 36 are mounted.

Each of the adjusting screws 35, 36 has one end engaged in a pocket or recess formed in the fixed mold member. As the screws 35, 36 are turned, the adjacent bar 34 will be moved towards or from the fixed member 10 and the strap 60 29 engaged against the sheet of paper 23, or released therefrom. The sheet of paper augments the action of the inserted section of insulation in preventing a too rapid absorption of heat from the cooling plate by the wall of the core 10 of 65 the casting box opposite the wall against which the matrix C is pressed.

The casting chamber or box formed by the coaction of the fixed and movable members 10 and 11 is closed at the bottom by the usual head gauge 70 38 and at the sides by hinged side bars designated generally at 39.

In order to lock the body portion or movable mold member 11 to the core member 10 preparatory to casting a printing plate 40, an operating lever 41 is provided. The lever 41 is fastened to a

shaft 42 having secured thereto a crank arm 43 hinged to one end of a link 44 the other end of which is similarly connected to a second crank arm 45 which is secured to a shaft 46. The shaft 42 has a pair of locking members 47, 48 secured 5 thereon, each of said locking members being provided with a slot 49 which is adapted to receive a pin (not shown) fastened in the movable portion of the machine. The shaft 46 is also provided with similarly formed locking members 51, 10 52 which coat with pins or members (not shown) in the movable mold member 11. When the handle 41 is manipulated the locking members 47, 48, 51, and 52 will be simultaneously moved 15 to lock the body portion or movable mold member 11 to the core member 10 or to release same when desired in accordance with well known practice. A head gauge 38 is provided which may have operating handles 53. For the purpose of retaining the movable mold member in the 20 horizontal position shown in dotted lines in Figure 1, a suitable retaining device, hinged to the frame 9 and indicated generally at 54, is also provided.

In operation and in accordance with the invention as described above, the casting chamber is prepared by securing a matrix C to the body portion or movable mold member 11 and then optionally confining a sheet of insulating material, preferably paper, to the inner wall of the core 30 member 10 by the clamping member or band 29 which is adjusted to clamp the paper or web 23 with the desired pressure by turning the spindles 24, thereby securing or adjusting the said paper 23 over the inner wall or surface of the core 35 member 10 of the casting box. Molten metal may now be poured into the open top of the mold to form a stereotype plate 40. The paper 23 will tend to prevent a too rapid chilling of the body portion of the printing plate, while the insulating material 22 secured in the recess 21 will act in a manner to prevent too rapid a cooling of the edges of the cast printing plate, where the major portions of the stresses due to uneven cooling are apt to take place while it is still in the casting 45 box, for reasons pointed out above. The cooling of the plate at the edges and on both sides of the body portion will now be approximately equal and as a consequence the said plate will have a homogeneous molecular structure so far as internal and marginal stresses and strains are concerned. The insulating material 22 it is to be understood plays the major part in preventing deformation of the stereotype plate due to the rapid cooling of the edges or margins of the 50 stereotype plate as compared to the body portion.

If desired, the movable mold member also may be recessed in the manner illustrated with regard to the fixed or core member in order to accommodate insulating material. As the distortion due to 60 the unequal cooling occurs mostly at the edges of the plate, it will be understood that heat insulating material on the margins of either or both of the movable and fixed mold members will retard the cooling of a plate during the process 65 of formation after the molten metal has been poured in the mold. In Figures 6 and 7, and from one side of Figure 4, the insulating material 22 has been omitted from the said recess 21 for the purpose of clearer illustration.

It will be understood that the invention may be embodied in other specific forms without departing from the spirit or essential attributes thereof, and it is therefore desired the present embodiment be considered in all respects as illustrative 70 75

and not restrictive, reference being had to the claims rather than to the foregoing description to indicate the scope of the invention.

What I claim is:

5 1. In a mold for casting curved stereotype printing plates, a concave mold member and a coacting convex mold member, means for securing a matrix to the concave mold member, shallow recesses extending along the edges of 10 said convex mold member, and heat insulating material in the recesses.

15 2. In a mold for casting curved stereotype printing plates, a concave mold member and a coacting convex mold member, means for securing 15 a matrix to the concave mold member, a recess in the convex member extending along its side edges and along its bottom edge only, and heat insulating material in the recess.

20 3. In a mold for casting curved stereotype printing plates, a concave mold member and a coacting convex mold member, means for securing a matrix to the concave mold member, recesses along the side edges and along the bottom edge only of the convex mold member, heat insulating material in the recesses, and means for 25 securing a sheet of paper over the casting surface of the convex mold member.

20 4. In a mold for casting stereotype printing plates, a first mold member and a second mold member which coact to form a casting chamber, means for securing a matrix to the first mold member, recesses in the second mold member along three of its edges, and heat insulating material in the recesses.

35 5. In a mold for casting stereotype printing plates, a first mold member and a second mold member which coact to form a casting chamber, means for securing a matrix to the first mold member, a recess in the second mold member

along its side and bottom edges only, and heat insulating material in the recess.

6. In a device of the kind described for casting stereotype printing plates, a movable member having a wall provided with means on an inner 5 surface thereof for securing a matrix thereto, a fixed member having a wall provided with marginally positioned means for securing heat insulating material thereto, and screw threaded means connected to the fixed member for adjustably clamping sheet insulating material to the wall of the fixed member, whereby molten metal poured into a chamber enclosed by the said walls of the fixed and movable members will 10 form a printing plate free from deformation and 15 stresses generally due to unequal absorption of heat while cooling.

7. In a device for casting printing plates, a movable member having a matrix receiving inner wall, a fixed member having a wall provided 20 with recesses arranged along said wall at the margins alone thereof for accommodating insulating material, and means including a band fastened to a member secured and adjustable 25 relatively to the fixed member for positioning 25 sheet insulating sheet material against the last mentioned wall.

8. In a stereotype plate casting mold, a first mold member and a second mold member each having a wall and arranged to cooperatively 30 form a casting chamber closed at the bottom and sides and open at the top, the first mold member having a relatively wide and shallow recess formed in its wall and arranged adjacent the bottom and side edges alone of the casting chamber, and heat insulating material in the recess; 35 whereby the cooling of the side and bottom edges of a plate cast in said mold will be retarded.

WILLIAM F. HUCK.
